CLAIM

The ornamental design for a combined clip-on handle and panel insert for cabinet doors, drawers or the like, substantially as shown and described.

DESCRIPTION

FIG. 1 is a reduced front perspective view of a combined clip-on handle and panel insert for cabinet doors, drawers or the like showing my new design;

FIG. 2 is a front elevational view thereof;

FIG. 3 is a side elevational view taken from the right of FIG. 1, the side opposite being a mirror image thereof, the section of a cabinet door being shown in broken lines for illustrative purposes only;

FIG. 4 is a rear elevational view thereof;

FIG. 5 is a top plan view thereof;

FIG. 6 is a bottom plan view thereof.

FIG. 1

FIG. 2
